UNITED STATES PATENT OFFICE.

RUFUS B. BULLOCK, OF ASHTABULA, OHIO, ASSIGNOR TO THE ASHTABULA CARRIAGE BOW COMPANY.

CARRIAGE-BOW.

SPECIFICATION forming part of Letters Patent No. 268,618, dated December 5, 1882.

Application filed May 11, 1882. (No model.)

To all whom it may concern:

Be it known that I, RUFUS B. BULLOCK, of Ashtabula, in the county of Sandusky and State of Ohio, have invented certain new and useful 5 Improvements in Carriage-Bows; and I do hereby declare the following to be a full, clear, and exact description of the invention, such as will enable others skilled in the art to which it pertains to make and use the same.

10 My invention relates to an improvement in covers for the side pieces of carriage-bows, the object being to economize in the quality as well as in the quantity of stock consumed, to reduce the amount of time and labor required to apply the covers to the minimum expenditure, and to produce a cover of superior beauty and durability.

15 Heretofore leather, canvas, drill, and other flexible covers have been secured to the side pieces of carriage-bows chiefly by sewing their edges together in an upturned position, thereby forming a welt, which not only gives the side piece an unfinished appearance and interferes with the operation of further dressing or 20 finishing the cover, but renders the side piece 25 unpleasant to grasp by the hand, and exposes the stitches to considerable strain and wear. In applying the covers by sewing, as above described, they are cut sufficiently large so 30 that after being passed around the side piece their edges will, after being brought in contact, be long enough to permit them to be readily clamped together to facilitate the operation of sewing. When this operation is concluded the clamps are removed and the edges 35 are trimmed down to the stitching. Aside from the objections above recited to this method of applying covers, it is expensive in that it involves a waste of stock, and because of the time 40 and labor required to prosecute it. It is also necessary that stock of superior quality be employed, otherwise the upturned and exposed edges will fray out. Flexible covers have also been secured to the side pieces of carriage-bows by wooden keys, which are driven or inserted into longitudinal slots formed in the side pieces and adapted to receive the edges of the covers, the said edges being retained in place by the keys. This method is, however, objectionable on account of the expense attending

it, because of the deterioration in the strength of the side pieces resulting from slotting them to receive the keys. It is also objectionable on account of the liability of the keys to swell and shrink and permit the edges of the covers 55 to work loose.

It is the object of my invention to apply covers to the side pieces of carriage-bows in such manner as to obviate the objections above set forth; and with this object in view my invention consists in a carriage-bow side piece provided with a cover the edges of which are united by a flat seam.

In the accompanying drawings, Figure 1 is 65 a view in side elevation of a side piece provided with a cover applied in accordance with my invention. Fig. 2 is a view thereof in transverse cross-section, and Fig. 3 is a view in perspective of a cover after its edges are joined and before its application to a side piece. 70

In prosecuting my invention the covers are cut of the exact size desired. Their edges are then united by stitching appropriate to bring the faces of the edges in close contact when the covers are expanded by being drawn over the 75 side pieces, the covers being preferably stitched before being applied to the side pieces.

A represents the side piece of a carriage-bow, provided with a flexible cover, B, of leather, canvas, drill, or any equivalent material, the 80 edges C of said cover being united by stitching, so as to bring their faces D in close contact, thus forming a flat seam. Parallel rows of short stitches E are exposed on the outer face of the cover, while the transverse strands 85 F, which join the edges, are concealed from view. The edges of the cover are preferably secured to the casing by cement, which acts as an auxiliary for holding them in place. This method of applying covers by flat seaming is 90 the most economical of material that can be adopted, as no more material is used than is sufficient to encircle the side pieces; and as the faces of the edges of the covers are protected against fraying, qualities of goods may 95 be employed for covers with excellent results which could not be employed for covers secured in the old way. By flat-seaming the covers they are rendered very neat in appearance, they are durable in use, the stitching is not 100

exposed to strain, and no obstacles are offered to the application of any finish which it is desired to impart to the covers after they are secured to the side pieces.

5 Having fully described my invention, what I claim as new, and desire to secure by Letters Patent, is—

1. A carriage-bow side piece provided with a cover the edges of which are drawn together to form a flat seam by appropriate stitching, as and for the purpose set forth.
2. A carriage-bow side piece provided with

a cover the squared edges of which are drawn together to form a flat seam by appropriate stitching, and united to the side piece by cement, substantially as and for the purpose de- 15 scribed.

In testimony whereof I have signed this specification in the presence of two subscribing witnesses.

RUFUS B. BULLOCK.
